Corporation, Cleveland, Ohio, a corporation of
Delaware

Original application February 18, 1935, Serial No.
7,114. Divided and this application April 30,
1937, Serial No. 139,958

5 Claims. (Cl. 18—8)

This invention relates to apparatus for the manufacture of thread or the like.

The present application is a division of prior application Serial No. 7,114, filed February 18, 5 1935, by Walter F. Knebusch and Alden H. Burkholder, in which is shown, described and broadly claimed apparatus suitable for the manufacture of thread or the like by a continuous process. On such apparatus the thread or the like, as, for 10 example, artificial silk thread manufactured by the viscose process, may be temporarily stored on each of a plurality of thread-storage, thread-advancing devices, suitable processing treatments being applied to the thread or the like while 15 stored on such devices. The thread-storage, thread-advancing devices may be mounted in stepped arrangement, the thread-receiving portion of each device other than the first being disposed in apposite relation to the thread discharge 20 portion of the preceding device. The apparatus illustrated in said prior application and herein specifically claimed is double sided, including two inclined banks of thread-storage, thread-advancing devices. Each bank comprises a number 25 of thread-storage, thread-advancing devices disposed to form a plurality of descending series.

In the accompanying drawings, Figure 1 is 30 an end elevation of a machine for the manufacture of thread or the like, said machine being of the kind shown and described in said prior application. Figure 2 is an end elevation corresponding to Figure 1, but on a larger scale, of 35 a portion of the machine. Figure 3 is a front elevation on the same scale as Figure 2 of the operating face of the machine shown on the right of Figure 1. In each of Figures 1, 2 and 3, parts have been omitted, either for the sake of clearness or in order to show the construction of the machine.

40 Figure 4 is a detail sectional elevation on a larger scale, on approximately lines 4—4 of Figure 5, through one form of thread-storage, thread-advancing device which may be used in machines embodying the present invention. Figure 45 5 is a plan, on a slightly smaller scale than that of Figure 4, illustrating several thread-storage, thread-advancing devices and associated portions of the apparatus, the cover of the gear housing being omitted. Figure 6 is an elevation 50 of the unsupported end of the thread-storage device of Figure 4. In the drawings, like reference characters refer to like parts throughout.

55 While the apparatus is capable of use in connection with the manufacture or processing of any kind of thread or the like, it will be de-

scribed hereinafter as applied to the manufacture of multiple filament viscose artificial silk thread.

The machine illustrated as embodying the invention comprises two banks of thread-storage, thread-advancing devices on each of which devices a great length of thread may be temporarily stored in a small compact space. The operating faces of said banks, i. e., the faces of the banks from which, for manipulation of the thread, access may be had to the thread-storage, 10 thread-advancing devices are oppositely disposed with respect to each other. Preferably, but not necessarily, the banks of thread-storage, thread-advancing devices are inclined toward each other, the means for forming the threads being disposed intermediate of and adjacent the upper ends of the banks. The threads, after leaving the thread-forming means, follow a descending course over a series of thread-storage, thread-advancing devices from the last of which they 15 proceed to the collecting means.

The thread-storage, thread-advancing devices may conveniently take the form of reels of a type later to be described which, during rotation thereof, wind and advance the thread in a plurality of spaced, generally helical turns. The 20 reels are preferably of cantilever form; i. e., supported and driven only from one end thereof. The reels in each bank are illustrated as disposed in a plurality of descending series. The reels in 25 each series are to advantage disposed in stepped arrangement with the receiving end of each reel immediately below the discharge end of the preceding reel. The discharge ends of the reels are thus presented toward the operating face of the 30 bank.

This arrangement of reels provides great advantages in permitting access to the reels for manipulation of the thread, inspection, repair, etc. Moreover, it is thereby possible to position 40 the reels in adjacent series in such relation to each other that corresponding reels are in corresponding positions. Thus the reels are in a sense disposed in a plurality of horizontal series which extend longitudinally of the machine. 45 This disposition of the reels results in simplification of the machine and provides important advantages in the construction of the driving means and processing apparatus.

In the machine illustrated in Figures 1, 2 and 50 3, the thread is formed in the usual manner by extrusion of the viscose through a spinneret into a coagulating bath 2. The thread resulting from coagulation of the viscose is led thence to the first thread-storage, thread-advancing reel 5, 55

upon which completion of coagulation is allowed to take place. From reel 5 it passes to any suitable number of other like devices 5a to 5i upon which are performed any desired processing steps. The thread is led from the last reel through a suitable guide to a collecting device such as cap twister 7.

The machine embodies a suitable frame including lower and upper platforms 8, 9, respectively 10 carried by cross beams 10, 11 supported by corner posts 12, the platforms 8, 9 being connected by diagonal uprights 13, 14. The driving mechanisms for the reels include a drive motor 18 mounted at one end of the machine as shown in Figure 3 the shaft of which actuates speed-reducing device 19 operating cross shaft 20 provided at its opposite ends with bevel gears 21 driving bevel gears 22 on diagonal shafts 23, of which one may be provided on the left side and 15 one on the right side of the machine as shown. Diagonal shafts 23 are provided at various levels with take-off drives for the reels 5a to 5i, inclusive. For convenience, the shafts 23 and drive connections therefrom to the several reels may 20 be located at one end of the machine as shown in Figures 2 and 3.

As the drive connection from the primary drive shaft 23 to each of the reels 5a to 5i is the same, a description of one will suffice for all. Thus, for the drive connection to each of the reels 5a to 5i, primary drive shaft 23 is provided with a spiral gear 60 driving a spiral gear 61 on a short horizontal shaft 62 parallel to the front of the machine, as shown in Figures 3 and 4. Shaft 35 62 is provided with a gear 63 which drives a gear 64 on a shaft 41 mounted on a slotted bracket 66 pivoted to turn about a shaft 67 and held in any desired position by cap screw 44 passing into the frame of the machine through a grooved slot in said bracket. Shaft 41 carries a gear 65 meshing with a gear 68 mounted for rotation with shaft 67. Shaft 67 extends horizontally and longitudinally along the operating face of the machine and is provided with driving means for the series of reels disposed along said shaft.

The means for driving each reel from the drive shaft 67 appears from Figures 4 and 5. As shown, the driving means may be inclosed in a longitudinally extending housing 76 which may 50 also serve as a lubricant reservoir for the parts therein and which may be provided with a removable cover 71. Drive shaft 67 extends longitudinally of the housing, its outwardly projecting ends being connected by couplings 75 to like ends of neighboring shaft sections. The shafts 72 for the reels are journaled in suitable bosses in the walls of the housing 76 and extend across the housing 76 and shaft 67.

In the apparatus shown, each reel in a horizontal series is mounted on one face of the housing 76 and is driven from drive shaft 67 by a spiral gear 70 mounted thereon and engaging a spiral gear 71 rotatably mounted on the reel drive shaft 72. Spiral gear 71 is provided with a clutch member 73a cooperating with a clutch member 73b splined to the shaft 72 and having a grooved collar 52. In the groove of collar 52 is disposed the fork 53 of a rod 54 connected to one arm of a bell crank lever 74. By suitable movement of the bell crank lever, the reel may be disengaged from the shaft 67. Each reel may, as shown, be provided with its individual clutch, the lever 74 for all of the reels being individually operated. However, for convenience, the levers 74 for reels 75 5a to 5i of a vertical series may be connected as

shown in Figures 2 and 3, by a bar 135 having an operating handle 136 at a convenient point, so that all of the reels in one vertical series may be started and stopped simultaneously.

The thread-storage, thread-advancing devices of the instant apparatus take the form of reels of the type shown in Figures 4 and 6, which reel is of the same general type and operates in the same manner as the reel shown, described and claimed in a prior application entitled "Winding 10 reel," Serial No. 652,089, filed January 16, 1933, by Walter F. Knebusch. The reel is, however, of cantilever form in the sense that it is supported from one end thereof, the thread-supporting bars of the reel being free and unobstructed at the other end of the reel. Therefore by rotating the reel in the proper direction to cause the turns of thread to travel from its supported end to its unsupported or free end, the task of transferring the thread from reel to reel is materially simplified, due to the absence of an extending shaft or any other obstruction at the unsupported end of the reel. The thread turns may be discharged from this end of the reel and transferred to the succeeding reel with no tangling about any obstruction at the free end of the reel, as would be the case with a reel supported at both ends. The unobstructed end of the reel permits ready accessibility to the reel for operating or other purposes.

The form of reel illustrated is made up of two interfitting rigid, generally cylindrical members respectively designated 80 and 81.

Member 80 may be termed the concentric member because it is concentric with, fixed to and rotates with the shaft 72. It comprises a body portion of generally cylindrical form having its periphery formed of a plurality of spaced bars 83, the body portion being mounted on a sleeve 84 keyed to the shaft 72 and held in place thereby by a nut 85 threaded upon the end of said shaft. Member 81 may be called the eccentric member because, while it is generally of cylindrical form, it is mounted with its axis laterally offset from and slightly inclined to the axis of the reel drive 45 shaft 72. The member 81, as shown, comprises a head formed of inner and outer rings 87, 88, the former of which has peripheral slots to receive the bars 89. The bars 89 are clamped between the rings 87, 88 which are held together by screws 81a. Inner ring 87 is mounted on a sleeve 90 journaled to rotate upon a supporting member 91 which surrounds shaft 72 and is spaced therefrom. Means are provided for supporting member 91 with its axis slightly offset laterally from and inclined with relation to the axis of shaft 72.

Rotation of the reel drive shaft 72 causes concentric member 80 fixed thereto to rotate, whereupon contact of its bar members 83 with bar members 89 of eccentric member 81 causes said eccentric member to rotate. The thread is thus caused to wind on the reel, the degree of the inclination between the axes of the reel members determining the lead or pitch of the turns of the thread. The thread is wound in generally helical form upon the reel and advanced lengthwise thereof. With a reel of this general type, any desired length of thread within reasonable limits may thus be continuously temporarily stored in a larger number of closely spaced turns.

Reels of the form shown in Figures 4 and 6 may be employed without change for each of the reels 5a to 5h, inclusive, Figures 1 and 2, since it is upon these reels that any wet processing operations are performed upon the thread. However,

it may be and ordinarily is desired to dry the thread on reel 5i before it is collected by cap twister 7. In this case, the reel 5i, while of the same general type and operated in the same general manner as the others, may supply a drying medium to the thread stored on the reel. Such drying medium is preferably supplied from the interior of the reel, entering the reel from a hollow driving shaft employed for the purpose.

10 The means for subjecting the thread to wet processing operations may conveniently take the form illustrated. Such means comprise reagent distributing systems for supplying processing liquid to the thread on the reel, a series of troughs 15 for collecting the processing liquid as it drains from the reel, and apparatus for recirculating the liquid or conducting it to the sewer. The individual reagent distributing systems, each of which serves corresponding reels in adjacent series, embodies a series of reagent distributors 115 positioned above the reels supplied from a common supply manifold 113 extending longitudinally of the machine. For each processing reagent there is a separate reagent distributing system of this 25 kind.

As shown in Figures 2, 3 and 5, troughs 108, suitably formed to collect the liquid and prevent splashing thereof, may be provided with a re-entrant portion 118 below the reel to allow the 30 transfer of the thread from the reel to the one below it. Because of the arrangement of the reels, it is possible to have one such trough serve several corresponding reels in adjacent processing series. Each trough 108 may communicate either 35 with a sewer, as when the liquid collected in the trough is wash water or some other liquid which is to be discarded, or a suitable recirculating and make-up system from which the liquid collected is passed to the corresponding supply conduit, if 40 the liquid collected in the trough is one which it is desired to re-use.

Referring to Figures 2 and 3 for other details of the apparatus shown, the collecting device comprises a cap-twister 7 of substantially standard form. Each descending series of reels is provided with one of said twisters, a plurality thereof being driven from the same power source. As in conventional practice, the illustrated machine is provided with a long drum 119 for each face 45 of the machine which drum 119 is connected by belts 120 to the cap-twister spindles, belts 120 having belt tighteners 120a. Drum 119 is driven by a belt 121 actuated from the drive shaft of the speed-reducing mechanism 19 which is driven by 50 motor 18.

For reciprocating the twister spindles a speed-reducing device 122 is provided, driven by a belt 123 from a pulley on shaft 20. The shaft 124 of such speed-reducing device is provided with a 55 cam 125 actuating a lever 126 pivotally mounted on the frame at 127 and connected by tension members 128 to lifting rods 129 on each side of the machine. Rods 129 on each side of the machine are slidable in vertical guides 130, and are 60 connected by a rail 131 which carries the rotatable spindles for the cap-twisters, the vertically moving parts being partly counterbalanced by weights 132. The function of drums 119 and cams 125 is to rotate and vertically reciprocate 65 the spindles of several cap-twisters.

Apparatus of the kind shown comprising two oppositely disposed inclined banks of thread-storage, thread-advancing devices provides numerous advantages. Machines of such form are 70 compact and economical of floor space; in fact,

it is doubtful whether, for a given production a more compact arrangement could be devised. Such machines lend themselves, furthermore, to designs which possess numerous advantages from an engineering standpoint. They are characterized by their low cost of construction. 5

In the case of the illustrated apparatus, the framework of the machine is such that the supports for the two inclined banks mutually contribute to support each other. In said apparatus, 10 for instance, the framework for the machine comprises inclined frame members which are joined together at the upper portions thereof and at the lower portions thereof. This results in a very strong, rigid construction which is of simple 15 design, which requires few parts, and which may be economically made. Furthermore, the illustrated construction provides a clear space inside the machine from which access may be had to interior portions of the machine for maintenance, 20 repair, and inspection purposes.

Moreover, machines of this type provide advantages in that other portions of the machine, in addition to the framework, may be common to the thread-storage, thread-advancing devices in 25 both banks. Thus in the illustrated apparatus the reels, spinning pumps, collecting devices, etc., for both sides of the machine are driven from a common source of power. Furthermore, processing reagents may be supplied from a common 30 source to corresponding reels on opposite sides of the machine, as is illustrated in the case of the above described embodiment of the invention in which, as shown in Figures 1 and 3 of the drawings, heated air for the drying reels in corresponding positions in opposite banks is supplied from a common heater 152, supplied by a blower 153, said heater communicating through manifolds 151 and ducts 150 with the reels. Consequently, a 35 high degree of uniformity of the thread produced on both sides of the machine is possible.

The platform 9 toward the upper portion of the machine is likewise common to the thread-forming means for both banks of reels.

Suitable means may be provided at each side of the machine from which an operator may have access to the reels on that side. In the illustrated apparatus, such means comprises a ladder 140 slideable along an operating face of the machine on track 141 on the floor and track 142 at the upper part of the machine. As in the case of an operator working on platform 9, an operator standing on such ladder performs only a certain class of operations at which he is particularly skilled. Thus there is an advantageous subdivision of labor in machines embodying the present invention, since each operator works at only one portion of the machine and performs only those tasks for which he is best fitted. Consequently machines of the present invention make possible the production of thread at very low 50 labor costs. 55

Various changes and modifications may be made in the illustrated embodiment of the invention without in any way departing from the spirit of the invention. Thus the invention is not restricted to the particular arrangements of the particular thread-storage, thread-advancing devices shown and described. The term "thread or the like" as used in the specification and claims hereof is not intended to be understood to be limited to thread in the narrow sense, but to apply to all materials which may be handled on such apparatus. 60 65 70 75 80 85 90 95 100

It is intended that the patent shall cover, by suitable expression in the appended claims, whatever features of patentable novelty reside in the invention.

5. What is claimed is:

1. Apparatus for the manufacture of thread or the like comprising two inclined banks of thread-storage, thread-advancing devices, the operating faces of said banks taking the form of oppositely disposed planes; a common frame structure supporting said banks; means associated with said common frame structure for forming thread or the like; and, disposed between the planes defined by the operating faces of said banks, common means for supplying treating media for processing the thread or the like stored on the thread-storage, thread-advancing devices of said banks, the arrangement of said common frame structure, said means for forming thread or the like, and said common supply means providing a substantially unobstructed space between said banks.

2. Apparatus for the manufacture of thread or the like comprising two inclined banks of thread-storage, thread-advancing devices, the operating faces of said banks taking the form of oppositely disposed planes; a common frame structure supporting said banks which frame structure is bent-shaped in cross section; means associated with said common frame structure for forming thread or the like; and, disposed between the planes defined by the operating faces of said banks, common means for supplying treating media for processing the thread or the like stored on the thread-storage, thread-advancing devices of said

banks, the arrangement of said common bent-shaped frame structure, said means for forming thread or the like, and said common supply means providing a substantially unobstructed space between said banks.

3. Apparatus for the manufacture of thread or the like comprising two inclined banks of thread-storage, thread-advancing devices, the operating faces of said banks taking the form of oppositely disposed planes; a common frame structure supporting said banks comprising inclined frame members connected together by cross-members; means supported from the upper ends of said inclined frame members for forming thread or the like; and, disposed between the planes defined by the operating faces of said banks, common means for supplying treating media for processing the thread or the like stored on the thread-storage, thread-advancing devices of said banks, the arrangement of said common frame structure, said means for forming thread or the like, and common supply means providing a substantially unobstructed space between said banks.

4. Apparatus as in claim 3 in which the means for forming the thread or the like comprise two coagulating baths disposed with their working faces in juxtaposition.

5. Apparatus as in claim 3 in which the means for forming the thread or the like comprise two coagulating baths each of which is supported from one of said inclined frame members.

WALTER F. KNEBUSCH.
ALDEN H. BURKHOLDER.
